UNITED STATES PATENT OFFICE.

DAVID G. MELVILLE, OF MEDFORD, ASSIGNOR TO THE ROXBURY CARPET COMPANY, OF BOSTON, MASSACHUSETTS.

DESIGN FOR A CARPET.

SPECIFICATION forming part of Design No. 14,361, dated October 23, 1883.

Application filed September 3, 1883. Term of patent 3½ years.

To all whom it may concern:

Be it known that I, DAVID G. MELVILLE, of Medford, in the county of Middlesex and State of Massachusetts, have invented a new and original Design for Carpets, of which the following is a specification.

The nature of my design is fully shown in the accompanying photographic illustrations.

The design is composed of the floral and foliage ornamentation arranged in bouquets or masses of various sizes, and having projecting sprays partially filling the intervening ground-work.

I claim—

The design for a carpet, substantially as is shown and described.

In testimony whereof I have signed my name to this specification, in the presence of two subscribing witnesses, this 29th day of August, 1883.

DAVID G. MELVILLE.
